UNITED STATES PATENT OFFICE.

FRANK F. TURNER, OF LITTLE FALLS, MINNESOTA.

HEATER.

Application filed April 7, 1928. Serial No. 288,228.

This invention relates to heaters and more particularly to that type of heater employed for heating residences.

An important object of the invention is to improve the structure of air or water heaters of this character to insure a more perfect heat transfer to the heated element.

A still further object of the invention is to produce a device of this character which 10 may be very readily constructed, which will be durable and efficient in service, which may be readily cleansed and which is a general improvement in the art.

A still further object of the invention is 15 to provide a structure such that the products of combustion are caused to travel through a course where they are constantly in contact with the conduit containing the element to be heated, thus avoiding those 20 losses occurring in the ordinary furnace construction, due to eddying of the products of combustion therein.

A further object of the invention is to 25 provide a construction, wherein the available heating surface is materially increased.

These and other objects I attain by the construction shown in the accompanying drawings, wherein for the purpose of illustration is shown a preferred embodiment 30 of my invention and wherein:—

Figure 1 is a vertical sectional view through a heater constructed in accordance with my invention, heaters being disclosed as disposed within an ornamental casing;

Figure 2 is a section on the line 2—2 of Figure 1;

Figure 3 is a section on the line 3—3 of Figure 2;

Figure 4 is a fragmentary detail view 40 showing a slightly modified form in which the outer wall of the casing is formed as a preheater.

The invention consists broadly in the provision of a sinuous duct 10 for the element to be heated and means coacting with this duct to produce at opposite sides thereof a series of chambers 11 in which each chamber is separated from the adjacent chamber of its series by a fold of the duct and is in communication with the chamber of the series at the opposite side of the duct which lies thereabove by a port 12 disposed at the peak of the fold, the lower arm 13 of which forms the upper wall of the chamber. Each 50 of the arms 13 and 14 of each of the sinuosities is so constructed that its under sur-

face inclines upwardly, with the result that products of combustion introduced to the lower chamber in any suitable manner will pass to the upper end of this chamber along 60 the upper wall thereof to the port 12 to a second chamber through which it will similarly pass until it has finally completed its travel through all of the chambers and has engaged against the upper wall of each of 65 the chambers.

As a convenient method of constructing the furnace embodying the invention, two of the ducts 10 are provided and are arranged, so that the chambers of the adjacent 70 faces thereof are in alignment with one another. The front and rear edge walls of the ducts are secured to front and rear wall structures 15 and 16, so that the ends of these chambers are concealed. The upper ends of 75 the ducts communicate with one another and with an outlet, as at 17, while the lower ends thereof are preferably extended vertically, as indicated at 18, to form the side walls of 80 a fire box 19 which may have arranged there- 80 in a grate 20 and all necessary accessories thereto. The upper ends of the confronting peaks of the ducts are connected by horizontal partitions 21. The front and rear walls 15 and 16 are connected by side walls 85 22 and these side walls are connected with the upper ends of the outwardly extending peaks of the ducts by partitions 23. The upper ends of the vertical sections 18 are 90 likewise connected to the side walls by partitions, indicated at 24. Each peak has ports 12 formed therethrough, so that products of combustion rising in the fire box pass outwardly through the ports 12, then 95 upwardly along the lower arms of outwardly extending peaks until they arrive at the space between the peak proper and the side walls when they pass through a second series of ports and upwardly along the lower arms of inwardly directed peaks. Here, 100 their travel is stopped by the partition 21 and they are again directed outwardly and the process repeated until entering the upper chambers 11, they pass to the smoke pipe 25.

By employing this structure, the products of combustion are maintained in engagement with the surface to be heated through their own tendency to rise, and there is no tendency of these products to separate from these surfaces, so that a maximum heat transfer is 110 obtained.

In construction of a furnace of this char-

acter, the lower chamber which actually forms the fire box may be provided with the usual fire door and each chamber thereabove will be in communication with a clean-out door 26 opening either through the front wall 15 or a side wall 22 of the furnace casing. Where the furnace is employed as a hot water or steam furnace, the outer casing of the furnace may conveniently be made double-walled and may form a preheater casing through which the water is conducted before being led to the lower end of the ducts 10.

10 I have found that by employing a structure of this character, the cost of heating is materially reduced and a heater structure provided which may be manufactured at a relatively low cost. Since the construction hereinbefore set forth is capable of a certain 20 range of change and modification without materially departing from the spirit of the invention, I do not limit myself to such specific structure except as hereinafter claimed.

I claim:—

25 1. In a heater, a substantially vertically extending sinuous duct for the medium to be heated, means coacting therewith producing a series of chambers at each side of the duct, the chambers of each series being partitioned 30 from each adjacent chamber of the series by a fold of the channel and being in communication with the overlying chamber of the series at the opposite side of the duct at the peak of said fold.

35 2. In a heater, a pair of sinuous ducts for the medium to be heated connected at their upper ends and combining to produce between their inner faces a vertical series of chambers, side walls coacting with the outer 40 faces of said ducts to produce at the outer face of each thereof a vertical series of chambers staggered with relation to the first named chambers, end walls for said chambers and ports conducting a heating medium from the upper end of each chamber of each 45 series to a higher chamber of one of the other series.

50 3. In a heater, a pair of sinuous ducts for the medium to be heated connected at their upper ends and combining to produce between their inner faces a vertical series of chambers, side walls coacting with the outer 55 faces of said ducts to produce at the outer face of each thereof a vertical series of chambers staggered with relation to the first named chambers, end walls for said chambers, and ports conducting a heating medium from the upper end of each chamber of each 60 series to a higher chamber of one of the other series, the upper walls of each chamber inclining upwardly toward said ports, the port leading from each chamber entering the communicating chamber at the lower end of the upper wall thereof.

65 4. In a heater, a pair of sinuous ducts for

the medium to be heated connected at their upper ends and combining to produce between their inner faces a vertical series of chambers, side walls coacting with the outer 70 faces of said ducts to produce at the outer face of each thereof a vertical series of chambers staggered with relation to the first named chambers, end walls for said chambers, and ports conducting a heating medium from the upper end of each chamber 75 of each series to a higher chamber of one of the other series, said ports crossing the duct.

5. In a heater, a pair of sinuous ducts for the medium to be heated connected at their 80 upper ends and combining to produce between their inner faces a vertical series of chambers, side walls coacting with the outer faces of said ducts to produce at the outer 85 faces of each thereof a vertical series of chambers staggered with relation to the first named chambers, end walls for said chambers, and ports conducting a heating medium from the upper end of each chamber of each 90 series to a higher chamber of one of the other series, the upper walls of each chamber inclining upwardly toward said ports, the port leading from each chamber entering the communicating chamber at the lower end of the upper wall thereof, said 95 ports crossing the duct.

6. In a heater, a pair of sinuous ducts for the medium to be heated connected at their upper ends and combining to produce between their inner faces a vertical series of 100 chambers, side walls coacting with the outer faces of said ducts to produce at the outer face of each thereof a vertical series of chambers staggered with relation to the first named chambers, end walls for said chambers, ports conducting a heating medium from the upper end of each chamber of each 105 series to a higher chamber of one of the other series, said end and side walls having openings permitting access to the chambers 110 and doors closing said openings.

7. In a heater, a pair of sinuous ducts for the medium to be heated connected at their upper ends and combining to produce between their inner faces a vertical series of 115 chambers, side walls coacting with the outer faces of said ducts to produce at the outer face of each thereof a vertical series of chambers staggered with relation to the first named chambers, end walls for said chambers, and ports conducting a heating medium from the upper end of each chamber of each 120 series to a higher chamber of one of the other series, the lower chamber of the first named series forming a fire box, the upper chamber thereof being adapted for connection with a smoke pipe.

8. In a heater, a pair of sinuous ducts for the medium to be heated connected at their upper ends and combining to produce be- 125

tween their inner faces a vertical series of chambers, side walls coacting with the outer faces of said ducts to produce at the outer face of each thereof a vertical series of 5 chambers staggered with relation to the first named chambers, end walls for said chambers, and ports conducting a heating medium from the upper end of each chamber of 10 one of the other series.

9. In a heater, a vertically sinuous duct for the medium to be heated, and means for conducting a heating medium from the bottom to the top of said duct at the exterior thereof alternately directing the heating 15 medium against the lower wall of folds at opposite sides of the duct.

In testimony whereof I hereunto affix my signature.

FRANK F. TURNER.
